(57) **CLAIM**

We claim the ornamental design for a case, as shown and described.

DESCRIPTION

FIG. 1 is a front perspective view of a case embodying my new design.

FIG. 2 is a rear perspective view thereof.

FIG. 3 is a front view thereof.

FIG. 4 is a rear view thereof.

FIG. 5 is a left side view thereof.

FIG. 6 is a right side view thereof.

FIG. 7 is a top end view thereof; and,

FIG. 8 is a bottom end view thereof.

The broken lines indicate portions of the case that form no part of the claimed design. The portions of the article shown broken away with wavy, parallel, broken cut-off lines indicate that any portion of the article beyond what is shown forms no part of the claimed design.
